UNITED STATES PATENT OFFICE

2,426,758

PAD RETAINING DEVICE

Alexander W. Whiteford, New York, N. Y.

Application December 31, 1946; Serial No. 719,364

1 Claim. (Cl. 128—153)

1

This invention relates to a device or appliance to be applied to a toe of a foot or a finger of a hand for retaining a medicated pad or wad of cotton on an infected or sore portion of said toe or finger.

It is an object of the invention to provide such a device which does not require the use of adhesive to removably secure the device on a toe or finger and overcomes the disadvantages of devices employing adhesive now in commercial use which cause irritation of the skin while on the toe or finger and laceration of the skin when removed from the toe or finger.

It is another object of the invention to provide a one piece device of this character produced from a web of suitable material by a single stamping operation.

Other objects and advantages of the invention will be disclosed in the detailed description of the invention.

In the drawing accompanying and forming a part of this application,

Figure 1 is a perspective view of the toe portion of a foot and showing by improved device applied to a toe thereof in medicated pad retaining position.

Figure 2 is a view, on an enlarged scale, of said device in extended flat condition.

Figure 3 is a side edge view of the device looking at the right hand side of Figure 2.

Figure 4 is a view of the device applied to a toe or finger and the end portions in interlocking engagement with each other and portions of the device in section.

Figure 5 is a view similar to Figure 2 but on a smaller scale than said Figure 2 and showing the end portions of greater length to permit a double interlocking of the end portions with each other.

Figure 6 is a view similar to Figure 4 and showing the device shown in Figure 5 applied to a toe or finger.

In Figures 1 to 4, inclusive, the embodiment of the invention comprises a strip stamped from a web of suitable pliable material, such as fabric or plastic sheet, and having a center portion 7 arranged with a center opening 8. Like end portions 9 and 10 are integral with and extended from diametrically opposite sections of the center portion and arranged with like slits 11 and 12, respectively, extending along the longitudinal center of the strip and terminating in spaced relation to the ends of the strip and the center portion 7.

In applying the device shown in Figures 1 to 4, inclusive, on a toe *t*, as shown in Figure 1, the

2

center portion 7 is engaged on a medicated pad or wad of cotton, indicated at *p* in Figures 1 and 4, applied to an infected or sore portion of the toe, the opening 8 centering the center portion 7 and pad *p* relative to each other. The end portions 9 and 10 are extended from the center portion 7 in opposite directions and around the toe until they meet when either of said end portions is passed through the slit in the other end portion 10 and the opposite end portions drawn in the direction in which they extend from the center portion to place the strip under tension and said tensional force of the strip retaining the engaged end portion in the slit. The material of the end portion 15 engaged in the slit extending from said slit will be bunched against the material bordering the slit and also tend to retain the strip under tension in toe encircling position. As shown in Figures 1 and 4, the end portion 9 is engaged in the slit 12 of the end portion 10 and the end portions 9 and 10 are drawn in the same direction in which they extend from the center portion 7 to place the strip under tension with the extremities of the end portions 9 and 10 extended over the opposite end portions 10 and 9, respectively, as shown at 13 and 14 in Figures 1 and 4.

The interlocking engagement of the end portions 9 and 10 may be reversed to that hereinbefore described by engaging the extremity 14 of the end portion 10 in the slit 11 of the end portion 9 and the extremities 13 and 14 extending in the same manner as that shown in Figures 1 and 4.

Figures 5 and 6 show a device similar to the device shown in Figures 1 to 4, inclusive, except that the end portions 15 and 16 are of greater length than the end portions 9 and 10, and the slits 17 and 18 are proportionally longer than the slits 11 and 12. The center portion 19 is of the same size and shape as the center portion 7 and arranged with a center opening 20 for centering the pad *p* relative to said center portion 19.

In applying the device shown in Figures 5 and 6, the center portion 19 is engaged on a pad *p* applied to an infected or sore portion of a toe *t* and the end portions 15 and 16 are extended in opposite directions around the toe and one end portion is passed through the slit in the other end portion and then subsequently the second end portion is passed through the slit in the first end portion and both end portions are drawn in the direction in which they were originally extended from the center portion 19 to place the strip under tension. As shown in Figure 6, the end portion 15 is first passed through the slit 18 in the

end portion 16, as at 21, and then subsequently the end portion 16 is passed through the slit 17 in the end portion 15, as at 21', and the extremities of the end portions 15 and 16 are extended, as shown at 22 and 23, respectively.

The strips as shown in Figures 2 and 5 may also be applied to a finger of a hand as well as to a toe as shown in the drawing, and said strips are stamped from a web of fabric or sheet plastic material by a single stroke of a die arranged to simultaneously sever the strip from the web and form the opening 8 or 20 and the slits 11, 12 or 17, 18 in said strip.

Having thus described my invention, I claim:

A pad retaining device consisting of a strip of pliable material having a center portion to engage a pad applied on a toe and end portions

adapted to be extended in opposite directions around the toe, and each end portion being arranged with a slit extending longitudinally thereof for the passage of one end portion through the slit in the opposite end portion to pull the strip taut and secure the strip on the toe in pad retaining position.

ALEXANDER W. WHITEFORD.
